(57) **CLAIM**

I claim the ornamental design for a stationary wall-mounted electric vehicle charger, as shown and described.

DESCRIPTION

FIG. 1 is a top perspective view of a reduced size, showing a stationary wall-mounted electric vehicle charger showing my new design;

FIG. 2 is a top perspective view thereof;

FIG. 3 is a front plan view thereof;

FIG. 4 is a side plan view thereof;

FIG. 5 is a side plan view thereof opposite FIG. 4;

FIG. 6 is a top plan view thereof;

FIG. 7 is a bottom plan view thereof; and,

FIG. 8 is a rear plan view thereof.

The broken lines in the figures depict portions of the stationary wall-mounted electric vehicle charger which form no part of the claimed design.
